United States Patent Office.

B. F. STURTEVANT, OF BOSTON, MASSACHUSETTS.

Letters Patent No. 92,489, dated July 13, 1869.

IMPROVEMENT IN PRESSURE-BLOWERS.

The Schedule referred to in these Letters Patent and making part of the same.

To all whom it may concern:

Be it known that I, B. F. STURTEVANT, of Boston, in the county of Suffolk, and State of Massachusetts, have invented an Improvement in Pressure-Blowers; and I do hereby declare that the following, taken in connection with the drawings which accompany and form part of this specification, is a description of my invention sufficient to enable those skilled in the art to practise it.

This invention consists in the arrangement, within the case of a fan-pressure-blower, which receives and delivers air around its axis, of deflecting-plates or partitions, which extend between one side of the outer case and a diaphragm-plate adjacent to one side of the fan-wheel, from near the central outlet-passage over the ends of the fan-blades, so as to intercept the air-currents as they are thrown off tangentially from the ends of the fan-blades, and to change their direction of motion, causing them to traverse in the channels formed between the side and periphery of the case and the diaphragm-plate adjacent to the fan and the interposed deflecting-plates or partitions, from the periphery of the case to the central discharge outlet.

It consists also in combining, with such a blower, a blower having a tangential outlet.

Figure 1, of the drawings, represents, in sectional elevation, a compound or multiplying pressure-blower, embodying my invention, one part, *a*, of the casing of one of the compounded blowers being removed to exhibit the interior construction, which is shown as looking from right to left of Figure 2, which is a vertical cross-section, taken in the plane of the axis of the blower-shaft, the section taken in fig. 1 being in the plane of the joint of the piece *a*, with the adjacent part of the blower-case.

But two blowers are shown in the drawings in combination, that number being sufficient to illustrate the application of my invention to a compound blower, though it will be obvious that more than two might be combined by mere multiplication or duplication of the central delivery-blowers.

Besides the piece *a*, the case of the central delivery-blower, containing the partitions *i*, is made up of a peripheral piece, *c*, and two sides, *d* and *e*, the latter piece, in the example shown, forming part of the case of an adjoining tangential delivery-blower, this case being composed of the continuation of *d*, so as to form half of the periphery, the other half being the piece *e*, which is provided with a side, *f*, having a central opening closed by the plate *g*, this blower being arranged to deliver air from the outlet *h*, in the direction of a tangent to the path described by the ends of the fans.

The space enclosed between the sides *d* and *e* of the central delivery-blower is considerably wider than is needed for the rotation of the fan-wheel in blowers which deliver air from a tangential outlet, and, as will be seen in fig. 1, the fan-wheel is located near the head *e*, through a central aperture in which, the air

enters to the fan-wheel, which being of a construction shown in patents previously granted me, will not be described herein, as not entering into the essence of my present invention.

Within the space between *d* and *e*, and adjacent to the side *d*, is a diaphragm, *b*, which makes substantially one boundary of the space in which the fan-wheel *j* revolves.

The diaphragm *b* is made, as shown, extending well over the ends of the fan-wheel blades, and in that part of *b* so extending, I cut openings, marked *k*, through which the air thrown off by the fan escapes into the space bounded by the parts *d*, *c*, *a*, and *b*.

As the air enters this space, it strikes against the partitions, stops, or deflectors *i*, which extend across it at intervals suited to the openings *k*.

The air on striking against the stops *i*, is thereby deflected, and rushes through the channels formed by the partitions *i*, between the diaphragm *b* and the blower-case to the central aperture in the head *d*, from which it may issue into a conduit, to be conducted in any direction or for any purpose, or it may, as shown in fig. 2, more especially, pass directly into an adjacent blower, at a central aperture in its side, which blower is constructed so as to deliver the air through the tangential outlet *h*.

The air-currents are indicated in the drawings by red arrows, and the direction of rotation of the blower-shaft by black arrows.

Previous to my invention, blowers have been made to deliver the air from a central outlet by the use of partitions between the side of the blower-case and a diaphragm interposed between said side and the adjacent side of the fan-wheel, but such partitions, if they extended to the outer corners of the fan-blades, did not extend over the ends of the blades, as mine do, so that a large portion of the power exerted in driving the fan-wheel was lost in propelling a current of air around the blower-case.

Now, by extending the partitions *i* over the ends of the fans, all of the air thrown off by them impinges at once against the described extensions of the partitions, and has its direction of motion changed so as to pass toward and out of the central outlet.

I claim a central outlet-blower, having its deflecting-plates extended over the ends of the fan-wheel blades, and between them and the blower-case, substantially as and for the purpose specified.

Also, a compounded blower, made up of one or more blowers, having central inlet and delivery-passages, diaphragms, and deflecting-plates, extending over the ends of the fan-wheel blades, combined with a tangential delivery-blower, substantially as described.

B. F. STURTEVANT.
